UNITED STATES PATENT OFFICE.

JAMES E. LOSE, OF WILKINSBURG, PENNSYLVANIA.

BLAST-FURNACE CASTING APPARATUS.

Application filed May 14, 1925. Serial No. 30,180.

This invention relates to blast furnace casting apparatus and more particularly to apparatus for handling and controlling the flow of molten materials issuing from the 5 tapping hole or iron notch of blast furnaces or similar smelting furnaces.

The principal object of this invention is to provide improved means for reclaiming or trapping the iron from the slag or cinder 10 which is skimmed from the iron during its flow through the apparatus.

Another object is to provide means for reclaiming or trapping the iron which will be automatic in operation, thereby eliminating 15 the manual labor heretofore necessary in operating the apparatus heretofore used for this purpose.

A further object is to provide apparatus having the novel design, arrangement, and 20 combination of parts hereinafter described and illustrated in the accompanying drawings.

In the drawings:

Figure 1 is a plan view of apparatus constructed in accordance with my invention.

Figure 2 is a sectional elevation on the line II—II of Figure 1.

Figure 3 is a sectional elevation on the line III—III of Figure 1.

Figure 4 is a sectional elevation on the line IV—IV of Figure 1.

Referring more particularly to the drawings, the numeral 2 designates a blast furnace provided with the usual iron notch or tapping hole 3 and with the customary cinder notch or cinder tapping hole 4. The cinder or slag which is flushed or tapped from the furnace through the notch 4 is led in the cinder runner trough 5 to the cinder ladle cars or other point of disposal.

The iron flowing from the furnace during the casting operation is handled or conveyed in a system of runners or troughs, which are preferably formed of cast metal, 45 made in sections of convenient length, to a series of branch runners or troughs leading each to an iron ladle car, in which cars the metal is removed in bulk and in a molten state from the blast furnace, or to a pig bed, 50 in cases where the metal is cast into pigs in the cast house of the furnace. The troughs are provided with suitable shutters or removable gates, by which the stream of molten metal is controlled and is directed 55 into different branch troughs in the usual

manner. The trough system comprises a skimming trough 6 leading from the iron notch or tapping hole 3 in the furnace 2, and connecting with a main iron runner or trough 8.

The trough 6 is provided with a dam 9, which is preferably formed integral therewith, and with a removable skimming barrier 10, which is adjustably held in the slots or recesses 10^a located in the opposite sides 60 of the trough 6. The trough 6 is also provided with a draining opening 11^a at a point above the dam, preferably in one of the side walls of the trough, as shown, in which case, the opening is closed by means of the shutter or gate 12, which consists of a vertically removable plate or metal block fitting within the grooves 12^a in the trough, and operatively connected with the hand lever 13. A second skimming barrier 14 is placed in the 70 trough 6, being located below the first skimming barrier 10 and above the dam 9 and projecting downwardly into the stream of molten iron. This skimming barrier also is 75 removably secured in the trough 6. The 80 draining opening 11^a in the trough 6 is provided with a branch or draining trough 18 which extends to a point above one of the iron ladle cars, or is connected with and 85 drains into the main iron runner or trough at a suitable point in its length, below the dam 9. The trough 6 is also provided at a point behind the skimming barrier 10 with a branch trough 16, which serves to carry 90 off the cinder or slag backed up in the skimming trough 6 by the barrier 10 during the casting operation.

The trough 16 is shallow throughout its length except at its rear portion immediately next to the trough 6 where it is deepened 95 forming a settling basin 17. The rear end of the basin 17 is as deep as the trough 6 and its bottom wall 17^a is inclined upwardly from the rear end of the basin forwardly to the normal bottom of the main portion of 100 the shallow trough 16.

The settling basin 17 permits any iron in the molten slag or cinder to settle out, and due to its location next to the trough 6 and 105 its inclined bottom wall the iron which settles out of the slag will flow back by gravity into the main body of iron in the trough 6.

The draining trough 18 is provided with 110 a removable dam 20, and, at a point above

- this dam the trough 18 is provided with a branch trough 21, which connects with and empties the trough 18 into the cinder trough 16. The trough 21 is provided with a removable overflow gate 22, which serves to raise the level of the molten materials behind the dam 20 while in place. The trough is also provided with a removable skimmer barrier 23, which is constructed to skim the cinder floating on top of the iron in the trough 18 and divert it into the trough 21 over the overflow gate 22, the iron continuing over the dam 20 and down the trough 18.
- 15 In the operation of my improved apparatus, the tapping hole 3 of the blast furnace is opened in the usual manner. The iron then flows from the furnace and down the trough 6 and backs up forming a pool 20 behind the dam 9, flows over the dam 9, and thence downwardly through the main iron trough 8 into the several branch troughs.
- 25 The skimming barrier 10 projects downwardly into the trough 6, the bottom edge of the skimming barrier being at or about the level of the top of the dam 9. The cinder flowing from the blast furnace with the iron, on account of being lighter, will 30 float on top of the molten iron, and on reaching the barrier 10 will be backed up in the trough behind the barrier. The heavier molten iron flows below the sheet of lighter molten cinder, under the barrier and 35 up over the dam, and then downwardly through the trough 8. The cinder backed up in the trough 6 by the skimming barrier is carried off sidewise by the cinder trough 16. The deepened portion or settling basin 40 at the rear or entrance end of the trough 16 serves to form a pool of cinder and iron which slows up the flow of the mixture so that the iron which is heavier than the cinder or slag will settle out of the cinder 45 and, due to the inclined bottom of the basin, will flow back into the main body of iron in the trough 6. The larger portion of the cinder continues on down the cinder trough 16 to the cinder ladle cars or other point 50 of disposal. At times considerable cinder having iron in the form of globules, which is known as buck shot, mixed with it, is carried in under the skimming barrier 10, and, in order to prevent the cinder being carried 55 over the dam and down the main iron trough 8, I provide the second skimming barrier 14, which is placed at a point in the trough 6 between the dam and the first skimming barrier 10, and projects down-
- wardly below the level of the top of the 60 stream of molten iron. After the casting operation has been completed, there is a considerable pool of molten iron remaining in the trough 6 behind the dam 9. The gate 12 in the drain trough 18 is then raised and 65 the pool of molten material is allowed to drain from the trough 6 and downwardly through the trough 18 which leads to the ladle cars. The removable dam 20 and gate 22 have been previously placed in position 70 in the trough 18. The molten materials flowing down the trough 18 are then separated, the skimmer 23 stopping the progress of the cinder down the trough 18 and causing it to be diverted over the overflow gate 75 22 and down the branch drain trough 21 into the cinder trough 16. The iron flowing down the trough 18 passes in under the skimmer 23 and over the dam 20 to the ladle cars or other point of disposition.
- 80 While I have shown and described only one specific embodiment of my invention, it will be understood that I do not wish to be limited thereto since various modifications in the construction and arrangement of the 85 several parts of the apparatus may be made without departing from the scope of my invention as defined in the appended claims.
- I claim:
1. The combination with a blast furnace 90 skimming trough having means for separating the molten cinder from the iron therein, separate troughs leading from said skimming trough for conducting away the separated iron and cinder, said cinder trough 95 having a deep portion at its juncture point with said skimming trough forming a settling basin in which iron may settle out of the cinder, said deep portion of said cinder trough being provided with a rearwardly 100 inclined bottom wall so that iron settling therein will flow back into said skimming trough.
2. In a blast furnace casting apparatus, a skimming trough having means for separating cinder from the iron flowing in said trough, a cinder overflow trough leading from said skimming trough, said overflow trough having a deep portion adjacent its juncture with said skimming trough forming 105 a settling basin in which iron may settle out of the cinder, and means for permitting the iron settled into said deep portion to flow back into said skimming trough by 110 gravity.
- 115 In testimony whereof, I have hereunto set my hand.

JAMES E. LOSE.
